COMBINED STENCIL-MOISTENING AND STENCIL-BLOTTING APPARATUS

Harmon P. Elliott, Watertown, Mass.

Application August 18, 1952, Serial No. 304,993

7 Claims. (Cl. 118—109)

1

This invention relates to improvements in stencil-moistening apparatus and more particularly to apparatus for moistening the tissue panels of printing stencils preparatory to forming the printing characters of a name and address, or other information, in the stencil tissues.

Names and addresses, or other information, which are to be borne by the tissue panels of printing stencils of the general variety employed in addressing machines and other business and statistical machines, are formed in the tissues by a typist who operates the conventional keys of a typewriter equipped with special means for holding a stencil. However, it is essential that each stencil tissue be preliminarily moistened so that the printing characters of the typewriter may be effectively cut or impressed in the stencil tissues. Ordinarily, the tissues have a thin film thereon and the printing characters are formed in the film while the latter is in a moist condition.

The stencil tissues may be moistened in various ways, such as by pressing a wetted wick against each tissue panel and maintaining them in contact for a suitable interval of time to enable the moisture to soften the tissue film, before the typist inserts any particular stencil in the typewriter. But, it is important to avoid excesses of surface moisture on the tissue panels. Otherwise, gumming of the type characters of the typewriter will occur after relatively short periods of use of the typewriter, and the excesses of moisture have other objectionable and deteriorating effects upon the typing mechanism.

In my Patent No. 2,584,683, dated February 5, 1952, there is disclosed a combined stencil-moistening and stencil-blotting apparatus wherein excesses of surface moisture on stencil panel tissue are removed prior to delivery of each moistened stencil to a pick-off position from which the typist removes it for insertion in a typewriter. The mentioned patented apparatus accomplishes its purpose efficiently and effectively but is relatively expensive.

It is among the objects of my present invention to provide a simplified relatively low-cost combined stencil-moistening and stencil-blotting apparatus which effectively moistens stencil tissues and which effectively removes excess surface moisture from each moistened stencil prior to its arrival at a pick-off position.

Another object of my present invention is to provide a combined stencil-moistening and stencil-blotting apparatus which may be substantially reduced in size as compared with my mentioned patented apparatus, and which is more readily

2

and conveniently actuatable by a typist to advance moistened and blotted stencils in succession to a pick-off position.

A further object of the invention is to provide a combined stencil-moistening and stencil-blotting apparatus wherein a moistening wick and a blotter are maintained by gravity in contact with the tissue panels of successive stencils at intervals between manual advances of successive stencils to a pick-off position, each advance of stencils being automatically preceded by a lifting of the stencils clear of the wick and blotter and being followed by an automatic return of the manually actuated advancing means.

It is moreover, my purpose and object generally to improve the structure and effectiveness of combined stencil-moistening and stencil-blotting apparatus and more especially such apparatus of the readily portable variety suitable for use by a typist engaged in forming printing characters in the tissues of stencils by means of a typewriter.

In the accompanying drawings:

Fig. 1 is a top plan view of a combined stencil moistening and stencil-blotting apparatus embodying features of the invention;

Fig. 2 is a side elevation of the apparatus of Fig. 1;

Fig. 3 is an end elevation of the apparatus of Figs. 1 and 2, looking at that end which is to the left in Figs. 1 and 2;

Fig. 4 is a cross-sectional view of line 4—4 of Fig. 1, on a larger scale, with a portion of the blotting member shown in elevation;

Fig. 5 is a cross-sectional view on line 5—5 of Fig. 4;

Fig. 6 is a plan view of the stencil-receiving end portions of the two stencil tracks, and showing the stencil pusher member mounted slidably on one of the tracks; and

Fig. 7 is an end elevation of the upper portions of the apparatus showing the stencil tracks and the stencils therein spaced above the moistening wick and blotter in the process of advancing the stencils along the tracks.

Referring to the drawings, a rectangular base container 10 may be equipped with the feet 12, of rubber or the like, for engaging the top of a desk or table or other support, on which the apparatus may be resting. The upper open side of container 10 is partially closed by a cover member indicated generally at 14 which includes the two forwardly projecting parallel arms 16 at opposite ends of the container, each of which has an upstanding flange 18 extending throughout its length and extending integrally rearward along

the cover member 14 to the rear side of container 10 where the cover member is hinged to posts 20 fixed to the opposite end walls of container 10, a pivot screw 22 passing through each post 20 and the adjacent flange 18 whereby the cover member 14 may be swung about the pivotal axis of the pivot screws 22.

Two guide rails or tracks 24, 26 are secured as by screws 28, to the under sides of arms 16 of cover member 14, the tracks extending in spaced parallelism from end to end of the container 10, and each track having a groove 30 in its edge which is toward the other track whereby the relatively rigid frame portions of stencils 32 may be slidably engaged in the edge grooves of the tracks and be pushed along the tracks with the tissue panels 33 of the stencils disposed between the tracks.

A conventional type of stencil holder 34 is secured to the tracks 24, 26, as by screws 36, and the holder 34 is located at the left hand end portions of the tracks in Figs. 1 and 2, and is adapted to contain a stack S of stencils with the lowermost stencil of the stack resting on the tracks. Each track 24, 26 has the upper wall of its edge groove cut away at 38 where the tracks extend under the holder 34, so that the lowermost stencil in stack S rests on the lower walls of the edge grooves as best seen in Fig. 6. Hence, this lowermost stencil is in position to be pushed along the tracks, to the right in Figs. 1 and 6, when a pusher member 40 is actuated to the right along track 24.

A stencil-moistening wick 42 is mounted within container 10 beneath the stack S of stencils, the wick being at a suitable elevation and of suitable shape, to contact substantially the entire area of the tissue panel 33 of that stencil which at any time is the lowermost stencil of the stack S, with gravity acting on the lowermost stencil in a manner to keep its tissue panel 32 pressed against wick 42. As shown, the wick 42 is a piece of sheet material draped over a support 44 which has generally the shape of the tissue panel 33, with the depending portions of the draped wick immersed in water, or other liquid, held in suitable quantity within a receptacle 46 which may be fixed within container 10 but which, preferably, is removably supported in a retainer 48 rigidly supported at a proper elevation by means of legs 50. The wick may be a sheet of sheepskin or other material having the property of conducting moisture from receptacle 46 to a stencil panel by capillary action.

According to the invention, each lowermost stencil 32 in stack S is first moistened by wick 42 and then is pushed along tracks 24, 26 to a blotting station at which excess surface moisture is removed from its tissue panel 33 by a blotting member indicated generally at 52 in Figs. 4 and 5. Blotting member 52 may be of any suitably moisture absorbent material which, when pressed against the moistened tissue panel of a stencil, will absorb any excesses of surface moisture on the panel prior to its advance along tracks 24, 26 to a pick-off position in which it projects substantially beyond the right hand ends of the tracks. The stencil 32 furthest to the right in Fig. 1 is in the pick-off position ready to be removed by a typist and inserted in a typewriter, with its tissue panel 33 thoroughly moistened but free of any excess surface moisture.

The blotting member 52 is herein shown as a sheet of moisture absorbent material wrapped around a support 54 having four right angularly

related plane sides, each having generally the shape and size of a stencil panel 33. The support 54 is rotatably mounted on uprights 56 within container 10 so that a ninety degree rotation of support 54 will present a fresh and relatively dry portion of blotting member 52 for blotting contact with a tissue panel of a stencil in the blotting position with gravity acting to maintain the stencil tissue in contact with blotting member 52 so long as cover member 14 is in its lowermost position. A knob 58 on one end of support 54 facilitates rotation of the blotting member 52, and a spring-pressed ball 60 is resiliently biased against a plate 62 on the support 54 and engages in detents 64 in plate 62 to yieldably retain the blotting member 52 in any one of its four operative positions.

Pusher member 40 is slidably mounted on track 24 with a rearwardly extending part 40' providing a shoulder 40^a for engaging back of the adjacent edge of the lowermost stencil in stack S for carrying this lowermost stencil to the right along the tracks when pusher member 40 is actuated to the right from its position of Figs. 1, 2 and 6. An upstanding arm 40^b is rigid on pusher member 40, and a relatively long rod 66 has one end fixed to arm 40^b and extends therefrom, to the right in Figs. 1, 2 and 6, in general parallelism with the tracks 24, 26. The right hand end of rod 66 has a stop collar 68 fixed thereon for engaging a bracket 70 through which the rod slidably extends, the bracket being secured to track 24 as by screws 72. A long coiled spring 74 is mounted on rod 66 with one of its ends engaging bracket 70 and its other end engaging arm 40^b, or the means securing the rod to arm 40^b, whereby the spring constantly biases pusher member 40 to its position of Figs. 1, 2 and 6, with collar 68 stopped against bracket 70. A movement of pusher member 40 to the right from its position of Figs. 1, 2 and 6 compresses spring 74 and pushes the lowermost stencil in stack S to the blotting position along tracks 24, 26 and this lowermost stencil pushes the stencil which was in the blotting position to the pick-off position. A forwardly projecting handle 76 on arm 40^b of the pusher member 40 facilitates manual movements of the latter to the right. When handle 76 is released after an actuation of pusher member 40 to the right, spring 74 restores the pusher member 40 to its position of Figs. 1, 2 and 6.

However, as pusher member 40 is actuated to push stencils along tracks 24, 26, it is essential that the stencils in the moistening and blotting positions be lifted clear of the wick 42 and blotting member 52. A roller 78 carried on pusher member 40 engages an inclined camming portion 80' of a rail 80 which is secured along the top margin of the front wall of container 10, interiorly of the container. The initial travel of pusher member 40 to the right in Figs. 1, 2 and 6 causes roller 78 to ride up the incline of camming portion 80' thereby to raise the pusher member 40 with a resulting up-swinging of cover member 14 about the axis of pivot screws 22. The tracks 24, 26 and the stencils therein are simultaneously carried upward to provide clearance for passage of the stencils along the tracks in spaced relation to the wick 42 and blotting member 52, as the pusher member 40 continues its travel to the right in Figs. 1, 2 and 6 with its roller 78 riding on the horizontal rail 80. The tracks and stencils continue elevated while the pusher member is being returned by spring 74 along the horizontal rail 80, dropping by gravity as the roller 78 rides down

the incline of camming portion 30' to bring the tissue panels of stencils which now are in moistening and blotting positions into contact with wick 42 and blotting member 52, respectively.

In use of the disclosed apparatus, the typist picks a stencil from the pick-off position and, after inserting it in her typewriter, forms desired printing characters on the tissue panel in the conventional manner. Meanwhile a moistened stencil will be in the blotting position and the lowermost stencil in stack S will be in contact with wick 42. When the typist is ready for another stencil, she merely actuates handle 76 to the right from its position of Figs. 1, 2 and 6, to advance the blotted stencil to pick-off position and the newly moistened stencil to blotting position. A stop S2 limits the travel of pusher member 40 to the right along track 24 to stop the pusher with its portion 40' under the right hand marginal portion of the stencil which will have become the lowermost stencil in the stack, so that the pusher can move back to the left without obstructing interference from the said lowermost stencil in the stack.

A resilient clamp 94 may be provided on one of the tracks for resiliently engaging each stencil in the pick-off position thereby to control the movements of the stencils.

It is intended that the patent shall cover, by suitable expression in the appended claims, whatever features of patentable novelty exist in the invention disclosed.

I claim as my invention:

1. In an apparatus for moistening stencils, a pair of tracks for slidably supporting a succession of stencils and along which the stencils are movable from a stencil-moistening position to a stencil-blotting position and thence to a pick-off position, a stencil holder secured to and above said tracks and adapted to hold a stack of stencils with the lowermost stencil in the stack resting on the tracks at said stencil-moistening position, a stencil-moistening element supported at said stencil-moistening position and engaging the under side of said lowermost stencil in the stack, a stencil-blotting element supported in said stencil-blotting position and engaging the under side of a stencil in said stencil-blotting position along said tracks, pusher means for advancing a said lowermost stencil in the stack along said tracks from said stencil-moistening position to said stencil-blotting position and for simultaneously advancing a stencil from said stencil-blotting position to said pick-off position, a stop for limiting each said stencil-advancing movement of the pusher, said stop being located to stop the pusher with a portion thereof under the stencil which will have become the lowermost stencil in the stack, means supporting said pair of tracks for upward movement away from said stencil-moistening and stencil-blotting elements, and mechanism responsive to a said stencil-advancing movement of said pusher means for raising said tracks and the stencils thereon away from said stencil-moistening and stencil-blotting elements.

2. In an apparatus for moistening stencils, a pair of tracks for slidably supporting a succession of stencils and along which the stencils are movable from a stencil-moistening position to a stencil-blotting position and thence to a pick-off position, a stencil holder secured to and above said tracks and adapted to hold a stack of stencils with the lowermost stencil in the stack resting on the tracks at said stencil-moistening po-

sition, a stencil-moistening element supported at said stencil-moistening position and engaging the under side of said lowermost stencil in the stack, a stencil-blotting element supported in said stencil-blotting position and engaging the under side of a stencil in said stencil-blotting position along said tracks, pusher means slidably mounted on one of said tracks and adapted to engage back of an edge of said lowermost stencil in the stack whereby a movement of the pusher means along its track pushes said lowermost stencil in the stack along the tracks to said stencil-blotting position and the stencil which was in the stencil-blotting position is simultaneously pushed along the tracks to said pick-off position, a stop for stopping a said movement of the pusher while a portion of the pusher is under the stencil which will have become the lowermost stencil in the stack, resilient means constantly biasing said pusher means to its position engaging back of an edge of the lowermost stencil in the stack and adapted to return the pusher means following each stencil-pushing movement thereof, means supporting said pair of tracks for upward movement away from said stencil-moistening and stencil-blotting elements, and mechanism responsive to each stencil pushing movement of the pusher means for raising said tracks and the stencils thereon away from said stencil-moistening and stencil-blotting elements.

3. Apparatus for moistening stencils, comprising a support, a member pivotally mounted on the support including a pair of rigid arms extending in spaced relation in directions away from the pivotal axis of said member, a pair of spaced and parallel tracks secured to said rigid arms and extending between the arms, a stencil holder secured to said tracks and adapted to hold a stack of stencils above the tracks with the lowermost stencil in the stack resting on the tracks at a stencil-moistening position, pusher means operable to push said lowermost stencil in the stack along said tracks to a stencil-blotting position with simultaneous advance of other stencils along the tracks, a stop for stopping a said movement of the pusher while a portion of the pusher is under the stencil which will have become the lowermost stencil in the stack, a stencil-moistening element on said support at said stencil moistening position, a stencil-blotting element on said support at said stencil-blotting position, said pivotally mounted member tending by gravity about its pivot in direction to maintain said lowermost stencil in the stack in contact with said stencil-moistening element, and to maintain a stencil in said stencil blotting position in contact with said stencil-blotting element, manual means on said pusher means for moving it in direction to push said stencils along the tracks, and cam means on said support for lifting said pivoted member about its pivot in response to a stencil-pushing movement of said pusher means, thereby to elevate said stencils above said stencil-moistening and stencil-blotting elements when said stencils are pushed along the tracks.

4. In a stencil-moistening apparatus, a pair of tracks along which stencils may be moved in succession from a stencil-moistening position to a stencil-blotting position and thence to a pick-off position, a stencil holder secured to said tracks at the stencil moistening position and holding a stack of stencils above the tracks with the lowermost stencil in the stack resting on the tracks, pusher means manually operable to push said

lowermost stencil along the tracks from said stencil-moistening position to said stencil-blotting position, the stencil which was in stencil-blotting position being simultaneously pushed along the tracks to said pick-off position, a stop for stopping a said movement of the pusher while a portion of the pusher is under the stencil which will have become the lowermost stencil in the stack, a stencil-moistening element supported at said stencil-moistening position and adapted to engage the under side of said lowermost stencil in the stack, a stencil-blotting element supported at said stencil-blotting position and adapted to engage the under side of the stencil which is in said stencil-blotting position, means supporting said pair of tracks for upward movement away from said stencil-moistening and stencil-blotting elements, and cam means responsive to a stencil-pushing movement of said pusher means for raising said tracks and stencils away from said stencil-moistening and stencil-blotting elements to provide clearance space for the movements of said pusher means and stencils.

5. In a stencil-moistening apparatus having a stencil-moistening element for engaging and moistening stencils arriving in intermittent succession at a stencil-moistening position, means for removing excess surface moisture from each said moistened stencil, comprising a stencil-blotting member adjacent to said stencil-moistening element and having a plurality of stencil-blotting surface portions, means rotatably supporting said stencil-blotting member at a stencil-blotting position whereby different stencil-blotting surface portions thereof may be moved selectively into stencil-blotting relation to a stencil in said stencil-blotting position, manually operable means for moving each moistened stencil from said stencil-moistening position into blotting coaction with said stencil-blotting member at said stencil-blotting position, means supporting all of the stencils for upward movement away from said stencil-moistening element and said stencil-blotting member, and mechanism responsive to each manual movement of said manually operable means for raising all of the stencils an appreciable distance above said stencil-moistening element and said stencil-blotting member while a stencil is being moved from said stencil-moistening position to said stencil-blotting position.

6. In a stencil-moistening apparatus having a stencil-moistening element for engaging and moistening stencils arriving in intermittent succession at a stencil-moistening position, means for removing excess surface moisture from each said moistened stencil, comprising a stencil-blotting member adjacent to said stencil-moistening element and having a plurality of stencil-blotting surface portions, means rotatably supporting said stencil-blotting member at a stencil-

blotting position whereby different stencil-blotting surface portions thereof may be moved selectively into stencil-blotting relation to a stencil in said stencil-blotting position, manually operable means for moving each moistened stencil from said stencil-moistening position into blotting coaction with said stencil-blotting member at said stencil-blotting position, means supporting all of the stencils for upward movement away from said stencil-moistening element and said stencil-blotting member, mechanism responsive to each manual movement of said manually operable means for raising all of the stencils an appreciable distance above said stencil-moistening element and said stencil-blotting member during movements of said stencils, and resilient means operative to restore the manually operable means to its original position following each manual operation thereof.

7. A stencil-moistening apparatus, comprising a base container open at its upper side, a member pivotally mounted on said base container, a pair of spaced and parallel tracks secured to said member, a stencil holder mounted on said tracks and adapted to hold a stack of stencils above the tracks with the lowermost stencil in the stack resting on the tracks at a stencil-moistening position, pusher means slideable on one of said tracks for pushing said lowermost stencil along the tracks from said stencil-moistening position to a stencil-blotting position, a stencil which was in the stencil-blotting position being simultaneously pushed along the tracks to a pick-off position, a stop for stopping a said movement of the pusher means while a portion thereof is under the stencil which will have become the lowermost stencil in the stack, a stencil-moistening element supported within said base container and adapted to be engaged by said lowermost stencil in the stack, a stencil-blotting element supported within said base container and adapted to be engaged by the stencil in said stencil-blotting position along the tracks, said pivotally mounted member tending by gravity about its pivot in direction to maintain said stencils pressed against the stencil-moistening and stencil-blotting elements, a handle on said pusher means for manual actuation of the pusher means in stencil-pushing direction along said tracks, cam means on said base container responsive to a said manual actuation of said pusher means for raising said pivotally mounted member, about its pivot to lift said stencils away from the stencil-moistening and stencil-blotting elements during movements of the pusher means and stencils, and resilient means for restoring said pusher means following each said manual actuation thereof.
